UNITED STATES PATENT OFFICE.

GOTTHILF ANSGARIUS BETULANDER, OF STOCKHOLM, SWEDEN.

AUTOMATIC TELEPHONE-EXCHANGE FOR DOUBLE-WIRE TELEPHONE SYSTEMS.

No. 835,878.

Specification of Letters Patent.

Patented Nov. 13, 1906.

Application filed April 5, 1904. Serial No. 201,683.

To all whom it may concern:

Be it known that I, GOTTHILF ANSGARIUS BETULANDER, a subject of the King of Sweden and Norway, and a resident of Stockholm, in the Kingdom of Sweden and Norway, have invented certain new and useful Improvements in Automatic Telephone-Exchanges for Double-Wire Telephone Systems, of which the following is a specification, reference being had therein to the accompanying drawings.

This invention relates to automatic telephone-exchanges for double-wire telephone systems of that kind where an earth connection is employed at the exchange during all the time used in automatically establishing telephonic communication between telephone-stations in the same or different communities and where a common battery placed at the automatic telephone-exchange supplies the current for establishing the desired connections.

The invention more particularly relates to automatic telephone-exchanges of the kind described in my application for Letters Patent, Serial No. 146,804, filed March 9, 1903, and has for its object to provide means whereby the automatic telephone-exchange can be adapted for use in larger telephone plants comprising any desired number of subscribers. To this end the movable part supporting the units-springs to be described is provided with one or several connecting-slides movable in their longitudinal direction, and only one of these slides is operated directly by the connecting-electromagnet.

The connection operation is performed in several distinct periods, and the slides are arranged in such a manner that during the first period of the connection operation only the slide operated directly by the connecting-electromagnet is moved forward step by step until, after the end of the first period of the connection operation, it is connected together in a determined position with the second slide.

Then during the second period of the connection operation these two slides are moved forward in mutually-fixed positions until, after the end of the second period of the connection operation, they are connected together with a third slide. Then during the third period of the connection operation these three slides are moved forward in mutually-fixed positions, and so on. During the last but one period of the connection operation the whole system of slides is connected to-

gether with the movable part carrying the units-springs, so that the said movable part is caused to follow the system of slides in a fixed position with relation to said slides during the last period of the connection operation. Taking a subscriber's number whatsoever—for instance, "4568"—the first figure "4" may belong to the first, the next figure "5" to the second, the next figure "6" to the third, and the last figure "8" to the fourth period of the connection operation. In this case after the first period of the connection operation the thousand-slide is connected together in a determined position with the hundreds-slide. After the second period of the connection operation these two slides are connected together in a determined position with the tens-slide, and after the third period of the connection operation all these slides are connected together in a determined position with the units-slide or the part carrying the units-springs.

In the drawings, Figure 1 is a diagram of a connecting apparatus adapted to be used in a telephone plant comprising two hundred and ninety-nine subscribers. Figs. 2 and 2bis taken together constitute a diagram showing the arrangement of the contact-field and the connections between two subscribers. For instance, between the subscriber No. 1 and that No. 235. Figs. 3, 4, and 5 are diagrammatic views, the first showing one slide, the second showing three slides, and the third showing four slides. These views are merely to illustrate the application of the invention to connecting apparatus having different numbers of slides.

Referring first to Fig. 1, the arrangement at the substation is as follows: Interposed in each line branch 1 and 2 is a switch or circuit-breaker 3, 4, respectively, and a contact-piece 5, 6, respectively, for connecting the corresponding line branch with the earth when required. One switch 3, hereinafter called the "connecting-switch," is used for establishing the desired connections and the other switch 4, hereinafter called the "disconnecting-switch," for disconnection. Normally—i. e., when the telephone-receiver TR is hanging upon its hook H—the following parts are bridged between the line branches 1 and 2—viz., switch 3, magneto-generator MG, signal-bell SB, switch-hook H, its lower contact-anvil LC, and switch 4. The secondary winding SW of the induction-coil and the

telephone-receiver TR are connected in parallel with hook H and short-circuited through the same. The primary circuit comprising the microphone-battery MB, the microphone M, the primary winding PW of the induction-coil, the contact-spring CS, and the contact C' is now broken, since the insulating-piece Y at the hook H keeps the contact-spring CS pressed down. When, however, the telephone-receiver TR is removed from its switch-hook, the latter is pressed by its spring against the upper contact UC, by which the magneto-generator MG and the signal-bell SB are short-circuited through the hook H, whereas the secondary winding SW of the induction-coil and the telephone-receiver TR are bridged between the line branches 1 and 2. At the same time the primary circuit is closed through the contact-spring CS and the contact-piece C'. The described arrangement at the substation is not essential, as it can be modified in several ways without departing from the spirit and scope of this invention.

25 The connecting apparatus connected with the subscriber's telephone apparatus comprises a connecting-electromagnet 9, a disconnecting-electromagnet 10, a locking-electromagnet 11, whose armature 33 normally prevents the armature 22 of the connecting-electromagnet from being attracted by the latter, and a cut-out electromagnet 12, serving to prevent the units-springs during the connection operation from making contact with connecting-wires leading to the connecting apparatus of subscribers with which no connection is desired. Of the two line branches 1 2 the one, 1, is connected with the connecting-electromagnet 9, as, also, through a wire 13 with one hundreds-spring 84, and the other line branch 2 is connected with the disconnecting-electromagnet 10, as, also, through a wire 14 with another hundreds-spring 85. The windings of the connecting and disconnecting electromagnets are connected together by a wire 17, and each of the said windings is further connected by a wire 18 19, respectively, with a contact 20 21, respectively, as shown in the drawings. The armatures 22 23 of the electromagnets 9 10 are electrically connected together by a wire 24 and further connected through the windings of the locking and cut-out electromagnets 11 12 and wires 25 26 with one pole of the connecting-battery 27, the other pole of which is connected with the earth.

In the form of embodiment of the invention shown in Fig. 1 there are two connecting-slides placed on the connecting-bar 29. When the connecting apparatus takes up its resting position, the two connecting-slides 71 72 are firmly coupled together with each other and with the bar 29; but during the connection operation the slides are disconnected and then coupled together one after the other.

with the slide, initiating the movement until at last the bar 29 is caused to move with the slides. Only one slide 71 (that which is first moved) is provided with connecting-teeth, preferably ten for each figure in the number 70 indicating the whole number of subscribers. Thus in the case of nine hundred and ninety-nine subscribers the slide 71 should have three into ten or thirty teeth corresponding to the teeth of the bar 29, (the units-slide,) 75 those of the tens-slide 72, and those of the hundreds-slide 71. In the case of nine thousand nine hundred and ninety-nine subscribers the slide 71 should have forty teeth, and so on. In Fig. 1, also, the slide 72 and the bar 80 85 90 are shown provided with teeth, but these have a quite other object than the connecting-teeth of slide 71, as they form, together with the levers 73 and 75, to be described, a sort of clutch by which the parts 72 and 29 are united, one after the other, with the slide 95 operated directly by the armature of the connecting-electromagnet 9.

As before mentioned, the connecting apparatus shown in the drawings is adapted for 90 a telephone plant comprising two hundred and ninety-nine subscribers. It has two slides 71 72, one of which, 72, is movably mounted upon the bar 29 and the second, 71, movably mounted upon the first slide 72. 95 Two slides will suffice up to nine hundred and ninety-nine subscribers. If it be desired to arrange the telephone-exchange for nine thousand nine hundred and ninety-nine subscribers, three slides would be necessary, one slide movable along the bar 29, a second slide moving along the first one, and a third slide moving along the second one.

The armature 22 of the connecting-electromagnet 9 is provided with a feeding-pawl 28, 105 or the like, engaging the notches of the slide 71. The armature 23 of the disconnecting-electromagnet 10 carries a locking-pawl 30, that when the disconnecting-electromagnet is energized and keeps its armature 23 attracted engages the notches of the slide 71 to prevent its falling down. When the current ceases to flow through the electromagnets 9 10, the armatures 22 23 are retracted by their springs 31 32, respectively, in the 110 positions shown in the drawings.

The coupling arrangement for coupling together the slides 71 and 72 may consist, for instance, of a lever 73, pivotally attached to the slide 71, said lever having a hook-shaped end engaging a notch 74 in the slide 72, and the coupling between the slide 72 and the bar 29 may consist of a lever 75, pivotally attached to the slide 72, said lever 75 having a hook-shaped end engaging a notch 76 in the 125 bar 29. Pivotally attached to each of the levers 73 75 is a catch 77 78, respectively, each catch being held by a spring 79 80, respectively, in a definite inclination to the corresponding lever 73 75, respectively. At 130

tached to the armature 33 of the locking-electromagnet 11 are pins 81 82, normally engaged by the free hook-shaped ends of the catches 77 78.

- 5 It will be seen from Fig. 1 that the hundreds-slide 71 does not carry any contacts. The hundreds-contacts are carried by the tens-slide 72 and the tens-contacts by the units slide or bar 29. The units-contacts are 10 lying in the connecting-field behind the connecting apparatus and are not movable. The hundreds-springs 84 85 86, Fig. 2, movable along the hundreds-contacts are attached to an insulating-plate 83, carried by the lever 73, and are raised and lowered with the hundreds-slide 71. The nine tens-springs 84^a to 86^c, movable along the tens-contacts, are attached to an insulating-plate carried by the lever 75 and move up and down with the 15 tens-slide 72. The units-springs 84^{a0} to 86^{c0} are attached in groups or sets to an insulating-piece fastened to the armature 37 of the cut-out electromagnet 12, carried by the connecting-bar 29, and are raised and lowered 20 with the said bar. In the diagrams shown in the drawings illustrating the connecting apparatus of a telephone-exchange comprising two hundred and ninety-nine subscribers there are only four hundreds-contacts for 25 each of the three hundreds-springs 84 to 86. In every vertical column the undermost contact is a reposing contact. The contact next above the reposing contact is a group contact of the first hundred, (one to ninety-nine.) 30 The next contact is a group-contact of the second hundred, (one hundred to one hundred and ninety-nine,) and the uppermost contact is a group-contact of the third hundred, (two hundred to two hundred and 35 ninety-nine.) Each of the hundreds-contacts is connected through a conducting-wire with one of the tens-springs 84^a to 86^c, respectively. The tens-contacts are also arranged in vertical columns, each column comprising eleven contacts. In each of these 40 vertical columns the lowermost contact is a reposing contact, the contact next above is a group-contact of the first ten, (one to nine,) the contact next above is a group-contact of the second ten, (ten to nineteen,) &c., and the uppermost contact is a group-contact of 45 the tenth ten, (ninety to ninety-nine.) Each tens-contact is connected through a conducting-wire with one of the units-springs 84^{a0} to 89^{c0}, respectively. The units-contacts are also arranged in vertical columns. Each 50 vertical column of contacts, corresponding to the springs 84^{a0} to 85^{b0}, comprises eleven contacts, and in each of these columns of contacts the undermost contact is a reposing-contact, the contact next above is a zero-contact, the contact next above is a one-contact, the contact next above is a two-contact, &c., and the uppermost contact is a 55 nine-contact. The units-contacts are con-

nected, through conducting-wires, with corresponding units-contacts at the other connecting apparatus. (See Fig. 2.)

When a subscriber wishes to put himself in communication with another, he closes one 70 of the earth contacts—for instance, 5—at his telephone apparatus and rotates the armature of his magneto-generator, whereby an alternating current passes through the magneto-generator MG, switch 3, line branch 1, 75 electromagnet 9, wire 17, electromagnet 10, line branch 2, switch 4, contact-anvil LC, switch-hook H, and signal-bell SB back to the magneto-generator. The electromagnet 10 then attracts its armature 23, thereby es- 80 tablishing the following circuit: earth, battery 27, wire 26, wire 25, electromagnets 12 and 11 in series, wire 24, armature 23, contact 21, wire 19, from which the circuit di- 85 vides into two branches, one comprising the wire 17, electromagnet 9, line branch 1, switch 3, contact 5, electromagnet E, (which is thus energized and closes the contact 6,) and earth, the other comprising the electromagnet 10, line branch 2, switch 4, contact 6, 90 and earth. The electromagnet 11 being energized, attracts its armature 33, thus releasing the armature 22, which is now attracted by its electromagnet 9. The current from battery 27 then after having passed the elec- 95 tronagnet 11 divides in two branches, one comprising the armature 22, contact 20, wire 18, electromagnet 9, line branch 1, and earth, the other comprising the armature 23, contact 21, wire 19, electromagnet 10, line 100 branch 2, and earth, the electromagnets 9 and 10 thus continuing holding their armatures in attracted positions. On account of the electromagnets 9 10 having attracted their armatures the feeding-pawl 28 has 105 passed the uppermost tooth of the slide 71 and entered into the notch beneath the said tooth, while the pawl 30 engages and aids in keeping the slide 71 in position. The lower end of the feeding-pawl has now passed the 110 upper end of the armature 23, whose upper end projects between the slide 71 and the feeding-pawl 28. If the connecting-switch 3 is now broken, the current from battery 27 ceases to flow through the electromagnet 9, 115 and the armature 22, with its feeding-pawl 28, is retracted by the spring 31, which now raises the slide 71 a distance corresponding to the length of a tooth equal to the vertical 120 distance between the several contacts at the connecting apparatus. As the armature 33 of the locking-electromagnet 11 is kept attracted during the whole period of the connection operation, the levers 73 and 75 are withdrawn from engagement with the slide 72 125 and bar 29, respectively, so that only the slide 71 is lifted. When the slide 71 is raised, the end of the pawl 30 slips over a tooth at the said slide and enters the notch nearest below that tooth, thus holding the slide in its 130

raised position when the connecting-switch 3 again closes the circuit through the electromagnet 9.

It follows from the preceding that if it be desired to raise the slide 71, say, four teeth four interruptions are to be made with the switch 3, the earth-contacts 5 6 being broken before the switch 3 is allowed to return and make contact after the fourth interruption. 10 On account of the break at the earth-contacts 5 6 the battery 27 ceases to supply current to the electromagnets, and the armature 23, with its pawl 30, is brought out of engagement with the slide 71, which is now kept in 15 its raised position only by pawl 28.

In order to further explain the connection operation, it may be supposed that the subscriber No. 1 (or, as we will hereinafter call it, "001") wishes to put himself in communication with the subscriber No. 235. He then by closing one of the earth-contacts 5 6 at his telephone apparatus, rotating his magneto-generator MG, opening the connecting-switch 3, closing the same, opening the connecting-switch for the second time, closing it again, opening it for the third time, breaking the earth-contacts 5 6, and closing the connecting-switch causes the hundreds-slide 71 to be fed three steps forward. When the armature 33 is attracted, the pins 81 82 cause the catches 77 78, pivotally attached to the levers 73 75, respectively, to move to the left, whereby the said levers 73 75 are caused to swing about their fulcrums, so that the lever 73 is withdrawn from the undermost notch 74 in the slide 72 and the lever 75 is withdrawn from the undermost notch 76 in the bar 29, by which the slide 72 and the bar 29 are released from engagement with the slide 71. At the same time the three hundreds-springs 84 to 86 are brought out of engagement with their contacts, which prevents any wear of the contact-springs and contact-pins as also forming of arcs between adjacent 45 contact-pins. By means of the three impulses the hundreds-slide 71 is raised a distance equal to the total length of three teeth, and the hundreds-springs 84 to 86 are thus brought to bear on the group-contacts of the 50 third hundred, (two hundred to two hundred and ninety-nine.) (See the left connecting apparatus C' in Fig. 2.) The slide 72 and the bar 29 remain in their resting positions, since the catches 77 78 are kept engaged by 55 the pins 81 82, respectively, during the whole period of the connection operation, and the electromagnet 11 is excited throughout the said period by the current through 27, 12, 11, 21, 10, 2, 4, 6, and earth.

60 It will be seen that during the forward movement of the slide 71 the catch 77 swings about the pin 81 as a fulcrum, but is not released before the end of the first period of the connection operation, when the circuit of the 65 connecting-battery 27 is opened at the earth-

contacts 5 and 6, so that the electromagnet 11 is deprived of current and the armature 33 is brought back by its spring. The pin 81 then gives the catch 77 free, and the spring 79 causes the said catch to take up its original 70 inclination to the lever 73, so that it does not follow the armature 33 when the latter is again attracted. On account of the slide 72, as also the bar 29, still occupying their original or lowermost positions the catch 78 is 75 still engaged by the pin 82, carried by the armature 33. As soon as the armature 33, on account of the electromagnet 11 having been deprived of current, is retracted by its spring and the catch 77, released by the pin 81, has 80 sprung upward the lever 73 under the influence of its own weight (or of a spring) catches into the slide 72; but as the slide 71 has been raised a distance equal to three teeth the lever 73 now catches into the fourth 85 notch 74 of the slide 72 and keeps the two slides 71 and 72 firmly united in such position. The slide 72 having not been raised, the lever 75, when the armature 33 is retracted into its resting position, again catches into 90 the undermost notch of the bar 29.

The subscriber No. 001 now during the second period of the connection operation produces a four-step movement of the slide 71 by making three breaks (instead of two) 95 at the switch 3. The armature 33 is attracted as before, and the pin 82 takes the catch 78, attached to the lever 75, with it, so that the said lever is caused to swing about its fulcrum and leaves the undermost notch 100 76 of the bar 29, whereas the catch 77 is not influenced on account of the spring 79 having caused it, after the armature 33 was retracted and the said catch released by the pin 81, to swing upward, and thereby to escape from the path of the pin 81. Thus the bar 29 is left in its resting position also during the second period of the connection operation, while the slides 71 and 72 are kept together by lever 73 in the relative position 110 determined during the first period of the connection operation. At the same time the nine springs 84^a to 86^c are removed from their respective contacts. By means of the four current impulses the slides 71 and 72 115 are together brought four steps forward, while the bar 29 remains at rest on account of the catch 78 retaining its engagement with pin 82 of the armature 33 during the whole period of the connection operation. After 120 the end of the second period of the connection operation the armature 33 returns to its reposing position, whereby the pin 82 releases the catch 78, which is then caused by its spring 80 to recover its original inclination 125 with respect to lever 75. The slide 71 has now been lifted a distance equal to seven teeth, while the slide 72, which is now joined with the slide 71, but which did not move during the first period of the connection op- 130

eration, has been lifted only a distance corresponding to four teeth. The lever 75 thus catches into the fifth notch 76 of the bar 29. The slides 71 and 72 being now joined together, the hundreds-springs 84 to 86 remain in contact with the group-contacts of the third hundred, (two hundred to two hundred and ninety-nine,) whereas the tens-springs 84^a to 86^a move along the tens-contacts until they stop in level with the group-contacts of the fourth ten (thirty to thirty-nine.) (See the left-hand side of Fig. 2, about the foot.) During the last period of the connection operation the subscriber No. 15 001 effects a six-step movement of the slides and bar. The whole system of slides being now joined together, the hundreds-springs and tens-springs remain pressing against their present contacts, while the units-springs are 20 brought to bear on the fives-contacts. (See Fig. 2.) The subscriber No. 001 has now brought himself in connection with the desired subscriber No. 235. The speaking-circuit is the following: telephone apparatus of 25 the subscriber No. 001, line branch 1, branch 13, group-spring 84 of the corresponding connecting apparatus C', (Fig. 2, left-hand side,) group-contact of the third hundred, group-spring 84^c, group-contact of the fourth ten, 30 contact-spring 84^c, corresponding fives-contact of the unit group, reposing contact of the units-spring 84^a at the connecting apparatus D' of subscriber No. 235, spring 84^a, reposing contact of spring 84^a, spring 84^a, 35 reposing contact of spring 84, spring 84, branch 13, line branch 1 of subscriber No. 235, telephone apparatus, line branch 2, branch 14, spring 85, reposing contact, spring 85^a, reposing contact, spring 85^a, reposing contact, sixth contact of spring 85^c 40 at the connecting apparatus C' of subscriber No. 001, spring 85^c, fourth tens-contact of spring 85^c, spring 85^c, third hundreds-contacts of spring 85, spring 85, branch 14, line branch 45 2, back to the telephone apparatus of subscriber No. 001.

In case the subscriber 235 desires to make connection with subscriber 001, he during the first period of the connection apparatus 50 effects a one-step movement. Then during the second period of the connection operation a new one-step movement and, finally, during the third period of the connection operation a two-step movement of slide 71. The connection in this case is to be seen in Fig. 2.

All these movements of connection are automatically performed by means of a controlling apparatus at the substation, so that the subscriber has only to turn a hand or 60 pointer and needs not think of the various makes and breaks of circuits.

The operation of restoring the connecting apparatus after the conversation is finished is performed by closing one of the earth contacts 5 or 6, rotating the magneto-generator 65

to send out an alternating current, breaking the disconnecting or restoring switch 4, breaking the earth contacts 5 and 6, and closing the switch 4, whereby the slides 71 72 and bar 29 fall directly down in their lowermost or original positions. It will be understood that when the disconnecting-switch 4 is opened the disconnecting-electromagnet 10 is deprived of current, whereby the armature 23 is retracted, said armature withdrawing the pawl 28 from engagement with the teeth of the slide 71, so that the whole system of movable parts falls down on account of it being not longer supported by pawl 28, whereby the hook-shaped lower end of the 80 lever 73 glides down along the teeth 74 of the slide 72, and the hook-shaped lower end of lever 75 moves along the teeth 76 of bar 29. As soon as the slides 71 and 72 and bar 29 reach their lowermost positions the catches 77 78 again take up their original positions with relation to the pins 81 and 82—i. e., the free hook-shaped end of the catch 77 engages the pin 81 and that of catch 78 engages pin 82.

It is clear that after the connection operation has been performed a calling-signal is to be given by rotating the magneto-generator to inform the called subscriber that a conversation is desired. The earth-contacts 5 and 6 then being opened, the armature 33 of the electromagnet 11 is not attracted, and a further movement of the slide system is therefore prevented.

The connection operation is thus performed in the following way:

I. *First period.*—First, closing one of the two earth contacts 5 or 6. Second, rotating the magneto-generator: electromagnets 9 and 10 excited, contact 21 closed, thus a circuit from battery 27 through magnets 12 and 11 105 in series and magnets 9 10 in parallel closed, the other of the two earth-contacts 5 and 6 automatically closed, armature 33 attracted (by which lever 73 is withdrawn from engagement with slide 72 and lever 75 is withdrawn 110 from engagement with bar 29, so that the said slide 72 and bar 29 are disconnected from slide 71,) armature 22 attracted, pawl 28 under the next tooth of slide 71. Third, breaking switch 3: line branch 1 and magnet 9 deprived of current, armature 22 retracted, thereby lifting the slide 71 one tooth, (repeated at every break at 3.) Fourth, breaking the earth-contacts 5 and 6 while still keeping switch 3 opened: all the magnets deprived of current, armature 23 retracted, pawl 30 thereby leaving slide 71, which is thus held in position only by pawl 28, catch 77 released from engagement with armature 33 and raised by its spring 79 into 115 its original inclination, lever 73 engaging slide 72 in its raised position, lever 75 engaging, as before, the undermost notch of bar 29.

II. *Second period.*—Fifth and sixth, closing one of the two earth contacts 5 or 6 and 120

rotating the magneto-generator: result as under first and second, with the difference that when the armature 33 is attracted only lever 75 is caused to swing, so that only bar 29 is disconnected, while the slides 71 and 72 are kept united by lever 73. Seventh, breaking switch 3: line branch 1 and magnet 9 deprived of current, armature 23 retracted, thereby raising slides 71 and 72 one tooth, (repeated at every break at 3.) Eighth, breaking the earth-contacts 5 and 6 while still keeping switch 3 opened: all the magnets deprived of current, armature 23 retracted, pawl 30 thereby leaving slide 71, which is again held in position only by pawl 28, catch 78 released from engagement with armature 33 and raised by its spring 80 into its original inclination, lever 75 engaging bar 29 in its raised position.

20. *III. Third period.*—Ninth and tenth, closing one of the two earth-contacts 5 or 6 and rotating the magneto-generator: result as under first and second, with the difference that when the armature 33 is attracted the slides 71 and 72 and bar 29 are still kept united together. Eleventh, breaking switch 3: line branch 1 and magnet 9 deprived of current, armature 23 retracted, thereby raising the slides 71 and 72 and bar 29 one tooth, (repeated at every break at 3.) Twelfth, breaking the two earth contacts 5 and 6 while still keeping switch 3 opened: all the magnets deprived of current, armature 23 retracted, pawl 30 thereby leaving slide 71, so that the whole system of slides is supported only by pawl 28. Thirteenth, calling the desired subscriber by the magneto-generator, magnets 9 and 10 excited, but without result, because the return-conductor to the connecting-battery 27 is broken.

40. *After the conversation is finished.*—Fourteenth and fifteenth. Closing one of the two earth contacts (5 or 6) and rotating the magneto-generator. Result as under ninth and tenth. Sixteenth. Breaking switch 4: magnet 10 deprived of current, armature 23 retracted, whereby the upper end of said armature withdraws the pawl 28 from engagement with slide 71, so that the whole system of slides falls down in its original position.

50. In the automatic telephone-exchange illustrated in the drawings an arrangement is provided for preventing any third subscriber from disturbing or overhearing the conversation between two subscribers. This arrangement comprises a number of units-springs 86^a to 86^a, 86^b to 86^b, and 86^c to 86^c, each of said springs being suitably provided with a roller at one end and connected at the other end through a tens-contact, spring 86^a, 86^b, 86^c, respectively, hundreds-contact, and spring 86 with a spring 40 entering between two contact-anvils 41 and 42, one of which, 41, is connected with one pole of a cut-out battery 45, while the other contact-anvil 42 is connected through the cut-out electromagnet 12 with the other pole of the said battery 45. The spring 40 normally bears on contact-anvil 41, but is attracted when the electromagnet 12 is excited against the contact-anvil 42. The springs 86^a to 86^a, 86^b to 86^b, and 86^c to 86^c normally bear on no contact; but when the bar 29 is raised one tooth each of the said springs will bear on a zero-contact, and when the bar 29 is raised one more tooth they will bear on a ones-contact, and so on, so that when the bar 29 is raised a distance equal to ten teeth they will bear on a nines-contact. Each units-contact of one connecting apparatus is connected with the corresponding units-contacts of the other connecting apparatus. Placed upon the connecting apparatus are, further, two springs 49, 50, one of which, 49, is connected through wires 51 and 44 with the battery 45 and the other, 50, through a wire 52 with one of the cut-out wires. The slide 71 further carries a knob 53, or the like, of insulating material, said knob having such a position that when the slide 71 takes up its lowest position, (see Fig. 1,) the springs 49, 50 are kept apart by the knob 53, whereas when the slide 71 is raised the knob 53 leaves the spring 50 and allows the latter to make contact with the spring 49. If now, as described, subscriber 001 has connected himself with subscriber 235, these two subscribers cannot be disturbed by a third subscriber. Suppose, for instance, a third subscriber wishing to put himself in connection with subscriber 235 after the connection between subscribers 001 and 235 has been performed. The third subscriber then has to bring his connecting apparatus into the same position as that of the connecting apparatus C', (Fig. 2, left-hand side.) During the three periods 105 of the connection operation the electromagnet 12 keeps its armature attracted so that at the connecting apparatus of the third subscriber spring 40 bears on contact-anvil 42. The units-springs 86^a to 86^c are thus kept 110 out of contact with the wire leading to the desired subscriber. When the connection operation was performed, the armature 37 at the connecting apparatus of the third subscriber, in case subscriber 235 was not busied, 115 would be retracted into its resting position on account of the circuit of the connecting-battery 27 being broken at the earth-contacts 5 and 6 of the third subscriber, and the connecting-springs would then come in contact 120 with their connecting-wires, respectively. In the present instance, however, this is not the case on account of the following circuit of the cut-out battery 45 being closed. First, following parts of the connecting apparatus of the third subscriber: electromagnet 12, contact-anvil 42, spring 40, spring 86, group-contact of the third hundred, spring 86^c, group-contact of the fourth ten, spring 86^c, then through the corre- 125

sponding cut-out wire, and, second, following parts of the connecting apparatus C': spring 86^{c3}, group-contact of the fourth ten, spring 86^c, group-contact of the third hundred, 5 spring 86, spring 40, and contact-anvil 41, back to battery 45. The electromagnet 12 of the third subscriber is thus still supplied with current, but now from battery 45, which is sending current through electromagnet 12 in the same direction as before the connecting-battery 27. A third subscriber therefore, cannot disturb the conversation between subscribers 001 and 235 by an attempt to connect himself with subscriber 15 235. In case he should try to connect himself with subscriber 001, a circuit would be closed from battery 45 through, first, following parts of the connecting apparatus of the third subscriber: electromagnet 12, contact-anvil 42, spring 40, spring 86, group-contact of the first hundred, spring 86^a, group-contact of the first ten, spring 86^c, cut-out wire, and, second, following parts of the connecting apparatus C': Springs 50 and 25 49 back to battery 45. It will thus be found that the connecting apparatus C', that has established the connection between the substations 001 and 235, connects that pole of the battery 45 which is not connected with the electromagnet 12 partly through contact-anvil 41, spring 40, spring 86, group-contact, spring 86^c, group-contact, and spring 86^{c3} 30 with a cut-out wire entering the connecting apparatus D' of the desired subscriber 235 and partly through the cut-out spring 49 50 with the cut-out wire of the connecting apparatus that establishes the connection, thus preventing all other subscribers from connecting themselves with any of the two subscribers connected together for conversation.

The constructions illustrated in Figs. 3, 4, and 5 will not require special description except to state that Fig. 3 shows a construction where but one slide is employed, Fig. 4 illustrates a construction where three slides are employed, and Fig. 5 illustrates a construction where four slides are employed. In Fig. 3 the slide is designated by the numeral 72. In Fig. 4 these features are designated by the numerals 72, 71, and 71^a. In Fig. 5 they are designated by the numerals 72 71 71^a 71^b. Having now described my invention, what I claim as new, and desire to secure by Letters Patent, is—

1. An automatic double-wire telephone system comprising a movable part, a slide arranged to move in the direction of movement of the said movable part, means for causing the slide to move step by step, in the direction of movement of the movable part during the first period of the connection operation, means for connecting together the slide and the movable part in a fixed position with relation to each other, means for feeding forward the slide together with the movable

part connected therewith in the same direction of movement during the second period of the connection operation, and means for restoring the slide and the movable part to their initial positions, substantially as described. 7c

2. An automatic double-wire telephone system comprising a movable part, a slide movable along the said movable part, a second slide movable along the first slide, means for causing the second slide to move step by step along the first slide during the first period of the connection operation, means for connecting together the slides, means for causing the slides to move together step by step along the movable part during the second period of the connection operation, means for connecting together the movable part with the two connected slides, means for feeding forward the slides and the movable part in fixed positions with relation to one another during the third period of the connection operation, and means for restoring the slides and the movable part to their initial positions, substantially as described. 75 80

3. An automatic double-wire telephone system comprising a movable part, a slide movable along the said movable part, a second slide movable along the first slide, a third slide movable along the second slide, 95 means for causing the third slide to move step by step along the second slide during the first period of the connection operation, means for connecting together the second slide with the third slide, means for causing the two connected slides to move step by step along the first slide during the second period of the connection operation, means for connecting all three slides together, means for causing the three connected slides to 100 move step by step along the movable part during the third period of the connection operation, means for connecting together the movable part with the three connected slides, means for feeding forward the slides and the 105 movable part in fixed positions with relation to one another during the fourth period of the connection operation, and means for restoring the slides and the movable part to their initial positions, substantially as described. 110 115

4. An automatic double-wire telephone system comprising a movable part, a slide movable along the said movable part, a second slide movable along the first slide, a third slide movable along the second slide, a fourth slide movable along the third slide, means for causing the fourth slide to move step by step along the third slide during the first period of the connection operation, 120 means for connecting together the third slide with the fourth slide, means for causing the two connected slides to move step by step along the second slide during the second period of the connection operation, means for 125 130

connecting together the second slide with the two connected slides, means for causing the three connected slides to move step by step along the first slide during the third period of 5 the connection operation, means for connecting all four slides together, means for causing the four connected slides to move step by step along the movable part during the fourth period of the connection operation, 10 means for connecting together the movable part with the four connected slides, means for feeding forward the slides and the mov-

able part in fixed positions with relation to one another during the fifth period of the connection operation, and means for restoring the slides and the movable part to their initial positions, substantially as described. 15

In witness whereof I have hereunto signed my name in the presence of two subscribing witnesses.

GOTTHILF ANSGARIUS BETULANDER.
